TABLE-TENNIS BAT

James L. Sewell, Akron, Ohio

Application February 16, 1940, Serial No. 319,270

2 Claims. (Cl. 273—76)

This invention relates to bats or paddles used in playing table-tennis, Ping-pong or like games.

Heretofore, table-tennis bats or paddles usually have comprised a thin ball-striking blade having a handle attached thereto, with a facing of non-skid sheet material, such as rubber, adhered on both sides of the blade, the edges of the facing material being exposed. The exposed edge portions of the facings were objectionable because they deflected the ball when struck thereby, and continued contact of the balls against the edges caused the facings to peel away from the blade, or the edges became worn and interfered with accurate use of the bat. Other objectionable features found in prior art bats are corrected in the present improved construction.

An object of this invention is to provide a bat of the class described having thereon non-skid facings, the edge portions of which will not materially deflect the playing balls in use of the bat, and in which said facings will not peel away from the bat upon continued striking of the balls adjacent the edges of the facings.

Another object of the invention is to provide a bat of the class described which is of durable, non-warping construction, and which readily adapts itself to provision of desired balance without necessarily affecting any given size or shape of the bat.

A further object of the invention is to provide a bat of the class described in which the balance is readily adjustable from or toward the central portion of the ball-striking blade, according to requirements of an individual user of the bat.

Another object of the invention is to provide a bat of the class described having the handle thereof integral with the ball-striking blade, and having improved thumb or finger grips in the handle adjacent the blade without weakening the connection between the handle and the blade.

Still another object of the invention is to provide comfortable and effective non-skid gripping portions in the handles of bats of the class described.

These and other objects of the invention will be manifest from the following brief description and the accompanying drawings.

Of the accompanying drawings:

Figure 1 is a front elevation of a table-tennis bat embodying the invention.

Figure 2 is a cross-section taken on line 2—2 of Figure 1.

Figure 3 is a cross-section taken on line 3—3 of Figure 1.

Figure 4 is a view similar to Figure 1, partly broken away, of a modified form of the invention.

Figure 5 is a cross-section taken on line 5—5 of Figure 4.

Figure 6 is a cross-section taken on line 6—6 of Figure 4.

Referring to Figures 1 to 3 of the drawings, the numeral 10 designates the ball-striking blade of a table-tennis bat, which may have an integral handle 11 of sufficiently greater thickness than the blade to provide the desired hand grip. For the purposes of this invention, the bat is preferably formed or molded from a transparent or translucent, moisture-proof, plastic material, such as the material known as "Tennite." The use of other materials capable of accomplishing the same results is contemplated, however.

Extending around the blade 10 and integral therewith, may be an outwardly rounded bead 12, of greater thickness than the blade to define shallow recesses 13, 13 on both sides of the blade. Adhered to the blades within recesses 13 may be facings 14 of rubber, or similar material, having non-skid designs or buttons 14^a, 14^a thereon, the ball-striking surfaces of the facings being substantially flush with opposite edges of the bead 12. With this construction, a ball striking near the edge portions of the bat will neither wear away the edges of the facings 14, nor strip the same from the blade. There being no exposed edges on the facings, the playing-ball will not be deflected thereby when the ball strikes close to the edge of the bat.

The handle 11 may be concavely recessed at 15, 15, on opposite sides adjacent the inner end thereof, to provide gripping portions for the fingers, particularly the thumb. Thus, the central portions of the handle curve inwardly toward edges of recesses 13, while the outer portions smoothly merge into the bead 12 at opposite edges of the blade to provide ribs 16, 16 for reinforcing the connection between the handle and the blade. Opposite sides of the handle are etched or roughened at 17 to provide a non-skid grip for the hand.

Handle 11 may be hollowed at 18 to balance the handle of the bat with the ball-striking blade. As this balance may vary according to the kind of material used, and the requirements of different individuals, the size and depth of hollow 18 may be varied in the manufacturing process to balance the bat as desired. Also, when more or less weight is required in the handle of the bat, a plug 19, adhesively secured in the outer end

of the handle, may be of increased or decreased size, respectively.

The bat shown in Figures 4 to 6 is similar to that described in connection with Figures 1 to 3, with the exception of certain modifications in the construction of the handle. For this reason like parts have been given like numerals.

On opposite sides of handle 11^a may be a shallow recess 20 within which is secured, by means of suitable adhesives, a sheet 21 of elastic or resilient material, such as rubber, preferably having non-skid buttons thereon, the outer surfaces of the buttons being substantially flush with the edges of recesses 21. This provides comfortable, efficient, non-skid gripping means for the hand.

Handle 11^a may be formed with a series of openings 22, 22 therein, tapering inwardly from the end of the handle, each opening being slightly smaller than the other to provide shoulder portions 22^a, 22^a. This provides means whereby the bat may be balanced from and toward the central portion of the blade 10, or the weight of the handle may be modified, by inserting plugs 23, 23 of varying sizes according to the requirements of a particular individual. Plug 19^a may also be modified in size for this purpose, this plug and plugs 23 being secured in place, as shown, by means of adhesives when the desired balance of the bat has been attained.

Thus may be provided means for carrying out the described objects of the invention. Modifications of the invention may be resorted to with-

out departing from the spirit thereof or the scope of the appended claims.

What is claimed is:

1. A bat of the class described comprising a ball-striking blade, a hollow handle on said blade, plugs of various sizes insertable in said handle, said hollow portion of said handle being formed with a series of recesses inwardly stepped from the end of the handle for receiving said plugs at various points in the handle as desired to fix the point of balance of the bat, said various plugs having different cross-sections for fitting different sizes of said stepped recesses.

15 2. A bat of the class described comprising a blade having a relatively thick handle formed integral therewith, said blade having a bead extending around the edge portions thereof, said bead being of greater thickness than said blade to provide recesses in opposite sides of the blade, 20 and facings of non-skid material secured within said recesses with the edges of the facings substantially flush with the edges of the recesses, said handle having concave finger-gripping recesses on opposite sides thereof tapering inwardly 25 toward the surfaces of said blade at the central portions thereof, the portions of the handle at the outer edges of said concave recesses merging into said bead to provide a reinforced connection between said handle and said blade where they merge together, said outer edge portions being raised respecting said recesses, providing ribs to prevent sidewise slippage of a finger gripped into either recess.

JAMES L. SEWELL.
